(57) **CLAIM**

The ornamental design for an electric power steering, as shown and described.

DESCRIPTION

FIG. 1 is a perspective view of the electric power steering;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is another perspective view thereof.

The broken lines shown in the drawings are included for the purpose of illustrating unclaimed portions of the electric power steering, and form no part of the claimed design.
